UNITED STATES PATENT OFFICE.

CARL ERIC ANDERSON, OF STRATFORD, CONNECTICUT, ASSIGNOR TO THE BRYANT ELECTRIC COMPANY, OF BRIDGEPORT, CONNECTICUT, A CORPORATION OF CONNECTICUT.

ELECTRIC SWITCH.

Application filed November 8, 1921. Serial No. 513,650.

To all whom it may concern:

Be it known that I, CARL ERIC ANDERSON, a citizen of the United States of America, residing at Stratford, in the county of Fairfield and State of Connecticut, have invented certain new and useful Improvements in Electric Switches, of which the following is a specification.

My invention relates to electric switches, and particularly to a momentary contact switch suitable for operating relays or remotely controlled electromagnets, etc. The object of the invention is to provide a simple and efficient device of compact construction, having certain features of improvement in construction and operation hereinafter described or illustrated in the accompanying drawings, in which

Fig. 1 is a plan of a switch in which my invention is embodied in one form;

Fig. 2 is a side elevation thereof;

Fig. 3 is a section on the line 3—3, Fig. 2;

Fig. 4 is a section on the line 4—4, Fig. 1;

Fig. 5 is a section on the line 5—5, Fig. 4;

Fig. 6 is a diagrammatic illustration of the operation of the switch; and

Fig. 7 is a perspective of one of the switch contacts.

In the form here shown, the present switch comprises an insulating body formed by a pair of insulating blocks 10 and 11 arranged face to face and united by suitable through screws 12 and 13. The screws take into a bracket 14, the legs of which are angled over the upper end of the switch body and tapped to receive screws 15 by which the switch carrying yoke 16 is secured in position. The latter is apertured at 17 to accommodate the thumb piece 18 of the switch operating lever 19, which projects therethrough and through the face plate, not shown, into position for manual operation.

The blocks 10 and 11 are appropriately recessed on their juxtaposed faces to afford a closed switch chamber 20. The switch contacts 21 and 22 project into the lower portion of the switch chamber and are connected to the wire terminals 23 and 24, which are of the same polarity. A third wire terminal 25, also mounted in the lower face of the block, is connected by the screw 26 to a strap 27 let into the outer face of the block 11 and connected at its opposite end by screw 28 to the switch frame 29.

The switch frame is of U-shape, and is se-

cured in position within the switch chamber by the screws 28 and 30, which pass through the block 11 and take into one side of the switch frame. The bridging portion of the latter is apertured at 31 to accommodate the switch lever 19, which is arranged between the sides of the frame and is pivoted on the pin 32 passing therethrough. The lever is preferably forked and its legs are notched at its lower end to receive the cross head 33 of the switch pin 34. At its opposite end, the pin passes through the end of the yoke 35 which straddles the switch frame and is pivoted on studs 36 outwardly offset from the side plates of the frame. To accommodate the oscillating yoke 35, the blocks 10 and 11 are recessed at 37 and 38 on opposite sides of the switch chamber, and the side plates of the frame 29 are shaped to the incline of the sides of the recesses 37 and 38 to cooperate with the latter, and forming stops which limit the throw of the yoke 35.

The operation of the switch will be readily understood. The lever 18 and yoke 35 form a toggle, subject to the action of the switch spring 39, which is confined between the cross head 33 of the contact pin 34 and the end of the oscillating yoke 35. When the lever 19 is swung on its axis 32, the cross head 33 of the switch pin is moved across the axis of oscillation 36 of the yoke 35, thereby further stressing the spring 39 and causing it to exert its effort against the yoke 35 in opposite direction. The yoke is thus biased with a snap action across its arc of travel. With the straightening of the toggle incident to this motion, the contact pin 34 is extruded through the end of the yoke 35 and as the latter swings to its opposite position the pin 34 engages the contact 21 or 22 with a wiping action. This effects a momentary completion of the circuit between the terminal 25 and the terminal 23 or 24, thus operating the remote control device in a manner well understood in the art.

As will be observed from the diagram (Fig. 6), the arcs described by the end of the pin 34 intersect at a point outside the area of the switch contacts 21 and 22, the latter being appropriately shaped to prevent the contact pin 34 from engaging both of the contacts on its travel in one direction. Thus, it is possible to arrange two distinct remote control devices in the two circuits from the terminals 23 and 24, each having a

common connection to the terminal 25. If a single remote control device is to be operated, a single switch contact may replace the contacts 21 and 22, being located at the point 5 40 at which the arcs of travel of the contact pin 34 intersects.

Various modifications in detail of construction and arrangement of parts will readily occur to those dealing with the problem, without, however, departing from what 10 I claim as my invention.

I claim—

1. An electric switch device comprising a spring toggle, and a guide pin for the 15 spring, in combination with a switch contact adapted to be momentarily engaged by said pin during its travel on the actuation of the toggle.

2. In an electric switch, a spring actuated 20 toggle comprising an oscillating member adapted to be biased on the actuation of the toggle, and a switch contact having a momentary wiping engagement with said biased member during its travel on the operation of the toggle.

3. In an electric switch, a switch frame, means for establishing constant electrical connection therewith, a spring toggle mechanism mounted in the frame and comprising 30 a member biased on the operation of the toggle, in combination with a contact adapted to be momentarily engaged by said member in the course of its travel following the operation of the toggle.

35 4. In an electric switch, a pair of switch contacts of the same polarity, a current-carrying toggle comprising a member adapted to engage one or the other of said contacts of the same polarity, with momentary wiping contact on the operation of the toggle.

5. In an electric switch, a switch frame, toggle mechanism mounted therein comprising an operating lever, an oscillating member, a toggle spring interposed between the 45 lever and oscillating member, and a guide pin therefor engaged by said switch lever

and oscillating member, and a contact momentarily engaged by said spring guide pin with a wiping action on the operation of the toggle.

50

6. In an electric switch, an insulating body comprising a pair of juxtaposed blocks of insulating material recessed on their meeting faces to form a switch chamber, wire terminals arranged at the lower end of the switch block, associated contacts projecting therefrom into the switch chamber, switch mechanism arranged in the chamber, and an operating lever therefor extending above the upper end of the insulating body, 60 a switch supporting frame mounted in the switch chamber, and means piercing the side of the insulating body for securing said frame in position.

7. In an electric switch, an insulating body comprising a pair of insulating blocks recessed on their meeting faces to form a switch chamber, a switch mechanism arranged therein and mounted on one of said blocks, wire terminals mounted on said 70 block outside the switch chamber and exposed for wiring, switch contacts projecting therefrom into the switch chamber, switch operating means projecting from the end of the body opposite the wiring terminals, a supporting bracket mounted on the side of the body, and screws piercing both blocks of said body and engaging said supporting bracket to hold the parts assembled.

8. In an electric switch, an insulating body comprising a pair of insulating blocks recessed on their meeting faces to afford a switch chamber, transversely extending screws for uniting said blocks, a bracket arranged at one side of the body and engaged by said screws, said bracket being angled over the top of the insulating body and adapted to receive screws for securing thereto a supporting yoke.

In testimony whereof I have signed my name to this specification.

CARL ERIC ANDERSON.
